(57) **CLAIM**

The ornamental design for a water flow shower valve, as shown and described.

DESCRIPTION

FIG. 1 is a front view of a water flow shower valve showing my new design.

FIG. 2 is a rear view of the water flow shower valve.

FIG. 3 is a right side view of the water flow shower valve.

FIG. 4 is a left side view of the water flow shower valve.

FIG. 5 is a top view of the water flow shower valve.

FIG. 6 is a bottom view of the water flow shower valve; and, FIG. 7 is a perspective view of the water flow shower valve. The broken lines shown in FIGS. 7 are for illustrative purposes only and form no part of the claimed design.
